UNITED STATES PATENT OFFICE.

PHILIP POVLOTZKY, OF CHICAGO, ILLINOIS.

STARTING DEVICE FOR INTERNAL-COMBUSTION ENGINES.

1,156,173.

Specification of Letters Patent.

Patented Oct. 12, 1915.

Application filed June 1, 1914. Serial No. 842,178.

To all whom it may concern:

Be it known that I, PHILIP POVLOTZKY, a citizen of the United States, residing at Chicago, in the county of Cook and State of Illinois, have invented certain new and useful Improvements in Starting Devices for Internal-Combustion Engines, of which the following is a specification.

This invention relates to that class of starting devices for internal-combustion engines in which a spring-motor is employed.

The invention has for its object to provide a novel and improved mechanism whereby the spring is rewound by the engine after the same has been started, and also to provide a novel and improved means for preventing overwinding of the spring, the winding mechanism being automatically uncoupled after the spring has been wound to a predetermined degree.

Other objects and advantages of the present invention will be pointed out in the detailed description appearing hereinafter, and in order that the invention may be better understood, reference is had to the accompanying drawings, in which—

Figure 1 is a plan view of the spring-actuated starting mechanism; Figs. 2 and 3 are elevations thereof from opposite sides; Fig. 4 is a longitudinal section on the line 4—4 of Fig. 1; Fig. 5 is an end view, partly broken away, looking in the direction of the arrow 5 in Fig. 1; Fig. 6 is a cross-section on the line 6—6 of Fig. 1; Fig. 7 is an end view looking in the direction of the arrow 7 in Fig. 1, and Figs. 8 and 9 are cross-sections on the lines 8—8 and 9—9, respectively, of Fig. 1.

Referring specifically to the drawings, 10 denotes a suitable base provided with bearing standards 11 in which are journaled trunnions 12 at the end of a barrel 13 inclosing a coiled spring 14. The trunnions are hollow and through the same passes a sleeve 15. The sleeve passes centrally through the barrel, to which latter the outer end of the spring is fastened, the inner end of the spring being made fast to the sleeve. In the sleeve is loosely mounted a starting shaft 16 which latter is coupled in any suitable manner to the engine shaft. The sleeve and the starting shaft are independently rotatable.

The following mechanism for winding the spring 14 from the engine is provided: On

one end of the spring barrel 13 is a worm gear 17 which meshes with a worm 18, the shaft 19 of which is supported by the base 10 and a bracket 20 carried by the latter. On the worm shaft 19 is a bevel gear 21 which is in mesh with a bevel gear 22, and on the shaft 23 of the bevel gear 22 is a sprocket wheel 24. A bearing standard 25 rising from the base 10 supports the shaft 23. On the projecting end of the shaft 16 which is adjacent to the worm gear 17 is loosely mounted a sprocket wheel 26 which is connected to the sprocket wheel 24 by a drive chain 27. Formed integral with, or fastened to the sprocket wheel 26, on one side thereof, is a disk 28. On the outer face of this disk is pivoted, at 29, a dog 30 having at one end a laterally projecting lug 31. The other end of the dog is connected by a link 32 to an arm 33 extending from a hub 34 loosely mounted on a hub extension 35 on the outer face of the disk 28. From the hub 34 also extends a second arm 36 to which is connected one end of a coiled spring 37 having its other end anchored to the disk 28. The parts 33, 34 and 36 form an angle lever which is fulcrumed on the part 35. Adjacent to the face of the disk 28 which carries the dog 30, is located a double cam 38 which is keyed or otherwise made fast to the starting shaft 16. This cam has two diametrically opposite abutments or shoulders 39 into the path of which the lug 31 extends. When the engine starts, the shaft 16 turns and rotates the cam 38, and when one of the shoulders 39 strikes the lug 31, the disk 28 is coupled to the cam to rotate therewith. The parts 26, 27, 24, 22, 21, 18 and 17 transmit the motion of the disk to the spring-barrel 13, and the spring 14 is thus wound up. This spring winding gear is a reducing gear so that the spring barrel turns at a greatly reduced rate of speed. For the initial starting of the engine, or in case of failure of the spring motor to operate, the shaft 16 may be operated manually by applying an ordinary starting crank thereto, the forward end of the shaft being squared for this purpose, as indicated at 40.

The energy stored up in the wound spring 14 is applied to the starting shaft 16, for turning the same to start the engine, by the following devices: The sleeve 15 projects from the trunnion 12 at the end of the barrel 13; opposite the end having the worm

gear 17, and on said projecting end is integral or made fast a clutch member 41 cooperating with a clutch member 42 keyed or otherwise made fast to the shaft 16. Between the clutch members is interposed a roller 43 which is wedged against the member 42 by a cam surface 44 on the member 41, and when thus wedged or bound, the motion of the member 41 is transmitted to the member 42. Any other suitable clutch mechanism may be provided for transmitting motion from the sleeve 15 to the shaft 16. The clutch member 42 runs loose and is not coupled to the member 41 when the shaft 16 turns in a direction to wind the spring 14, but when the sleeve 15 is rotated by the spring 14, the members 41 and 42 are coupled together, and the sleeve is thus coupled to the shaft to turn the latter. When the spring 14 is being wound up, and after it is wound, the sleeve 15 is locked against rotation until a starting impulse is desired, by the following mechanism:

The clutch member 41 has a rim portion 45 provided with a stop shoulder 46 which intercepts a shoulder 47 on a manually operated lever 48 fulcrumed on the base 10, as indicated at 49. A spring 50, connected to the lever, holds the latter in contact with the periphery of the part 45. A guide bracket 50^a for the lever is provided. When the shoulders 46 and 47 are in contact with each other, the sleeve 15 is locked against rotation by the spring 14, and upon swinging the lever to disengage the shoulders, the sleeve is released and turned by the spring, whereupon the motion of the sleeve is transmitted to the shaft 16 by the clutch mechanism 41, 42 and 43 hereinbefore described, and a starting impulse is given said shaft.

In order to hold the lever 48 in releasing position until the end of the starting impulse of the shaft 16, the following devices are provided: In suitable bearings 51 on the base 10 is mounted a shaft 52 on which is fast a ratchet wheel 53, which is engageable by a spring pawl 54 carried by a lever 55 which is fulcrumed on said shaft. The shaft is given a step-by-step rotary motion through this pawl-and-ratchet mechanism. The lever 55 is actuated by an eccentric 56 on the sleeve 15, the strap 57 of the eccentric having a rod 58 which is connected to the lever. On the shaft 52 is also fast a cam 59 having diametrically opposite shoulders 60. To the lever 48 is fastened one end of an arm 61 having at its opposite end a laterally projecting finger 62 which rests on the periphery of the cam 59. The finger 62 is normally adjacent to and behind one of the shoulders 60. On the periphery of the part 45 is a cam 63 which is located to come against the edge of the lever 48 and force the same in the direction it swings to disengage the shoulders 46 and 47. When the lever 48 is

swung to release the sleeve 15 as hereinbefore described, the cam 63, shortly after the clutch member 41 starts to turn, strikes the lever 48 and forces it farther away from the periphery of the part 45, whereupon the arm 61 swings upward and the finger 62 rises over the shoulder 60 and engages the high portion of the cam 59, which latter now, through the arm 61 holds the lever 48 retracted. In the meantime, the rotation of the sleeve 15, through the eccentric 56 and the pawl-and-ratchet mechanism 53, 54 and 55, imparts a step-by-step rotary movement to the shaft 52 and the cam 59 turns. At the end of the starting impulse, the cam has been rotated sufficiently to bring the next shoulder 60 adjacent to the finger 62, whereupon the arm 61 is released, and the lever 48 is now drawn back by the spring 50 to position the shoulder 47 so as to intercept the shoulder 46, and when said shoulders meet, the sleeve 15 is locked against further rotation.

To prevent overwinding of the spring 14 by the engine, the following mechanism is provided for automatically disconnecting the disk 28 from the cam 38, after the shaft 16 has been given a predetermined number of revolutions by the engine shaft to wind up the spring. This mechanism comprises the following parts: On the trunnion 12, adjacent to the eccentric 56, is an eccentric 64 the strap 65 of which has a rod 66 which is connected to a ratchet-lever 67 fulcrumed on the shaft 52. The ratchet-lever carries a spring pawl 68 which engages the ratchet wheel 53 on one side of the spring pawl 54, said ratchet wheel being wide enough to accommodate both of said pawls. On the shaft 52 is also fast a cam 69 the periphery of which is engaged by a finger 70 at the outer end of a rocker arm 71 fixed to a rock shaft 72 extending parallel to the axis of the barrel 13 and supported at its end in bearings 73 on the base 10. The forward end of the shaft 72 has a finger 74 which is designed to come into the path of the arm 36. On the base 10 is also pivoted, as indicated at 75, a detent 76 which is so positioned that it may engage a shoulder 77 on the periphery of the disk 28. A coiled spring 78 anchored to the base 10 and connected to the detent tends to swing the same toward the periphery of the shoulder 77. The detent is located slightly in advance of the finger 74, to one side thereof, and has a hook 79 which extends around the back of the finger, whereby a loose connection between the finger and the detent is provided, and the latter is caused to swing away from the shoulder 77 when the finger 74 is retracted.

The finger 74 and the detent 76 are in retracted position when the finger 70 of the rocker arm 71 engages the high surface of

the cam 69. When the barrel 13 is rotated by the engine to wind the spring 14 in the manner hereinbefore described, the cam 69 is rotated step-by-step through the eccentric 64 and the pawl-and-ratchet mechanism 67, 68 and 53, and when the finger 70 reaches the end of the high portion of the cam, the rocker arm is released and swung down by a coiled spring 78^a connected to it, whereupon the shaft 72 is rocked and the finger 74 swings forward to intercept the arm 36. When the arm 36 strikes the finger 74 the arm 33 swings, and through the link 32 the dog 30 is swung to disengage the lug 31 from the shoulder 30. The cam 38 is now disconnected from the disk 28, and the spring winding mechanism is disconnected from the shaft 16. At the same time the finger 74 swings forward to intercept the arm 36, the detent 76 is swung over by its spring 78 to intercept the shoulder 77 and lock the disk 28, which locks the barrel 13 and prevents the spring from unwinding. The arm 36 swings between stop pins 79^a projecting from the face of the disk 28. The spring 14 being now wound, the barrel 13 is locked against rotation by the locking of the disk 28 as hereinbefore described. When the spring is being wound up as described by the rotation of the barrel 13, the sleeve 15 is held stationary by the lever 48 as hereinbefore described. When the sleeve 15 is released to impart a starting impulse, and the shaft 52 is rotated by the pawl-and-ratchet mechanism 53, 54 and 55 to actuate the cam 59, the cam 69 is also rotated as it is fast on the shaft 52. At the end of the starting impulse the cam 69 will have swung the arm 71 to rock the shaft 72 in a direction to retract the finger 74 and the detent 76, whereupon the spring 37 rocks the arms 36 and 33, and the latter, through the link 32, swings the dog 30 so that its lug 31 again intercepts one of the shoulders 39, which again couples the winding mechanism to the shaft 16, and the spring 14 is rewound from the engine.

The various gears and other parts are so designed and proportioned that the spring 14 turns the shaft 16 a few times, just enough to start the engine, whereas a greater number of revolutions of said shaft are required to wind up the spring.

As the ratchet levers 55 and 67 do not operate together, one of the pawls acts to prevent the ratchet wheel from slipping back when the other pawl is making a back stroke. The eccentric 64 is so positioned that the finger 74 is advanced at the proper time to come squarely under the arm 36 in order that there may be no edgewise contact therebetween.

The spring 14 is so designed that when it has unwound and started the engine, the shoulder 46 is spaced a short distance from

the shoulder 47. It will therefore be evident that when the winding action starts, the sleeve 15 is not being held and the part 45 then turns slowly until the shoulders come together, whereupon the sleeve is locked and the spring commences to wind. Thus no brake is required to check the starting impulse, and the engine is also given enough time to pick up a little speed. To start the winding of the spring immediately after the engine starts is objectionable as it places too much load on the engine at a time when its strokes are slow and of minimum power.

I claim:

1. In a starting device for internal-combustion engines, a starting shaft, a sleeve loosely mounted on said shaft, a rotatable member loosely mounted on the sleeve, a spring connected at one end to said member and at the other end to the sleeve, a rotatable element loose on the shaft, a pivoted clutch member carried by said element, a rotatable member fast on the starting shaft and having an abutment engageable by the clutch member, a gearing between the rotatable element and the first-mentioned rotatable member for turning the latter in a direction to wind the spring, and means controlled by the first-mentioned rotatable member for tripping the clutch member.

2. In a starting device for internal-combustion engines, a starting shaft, a sleeve loosely mounted on said shaft, a rotatable member loosely mounted on the sleeve, a spring connected at one end to said member and at the other end to the sleeve, a rotatable element loose on the shaft, a pivoted clutch member carried by said element, a rotatable member fast on the starting shaft and having an abutment engageable by the clutch member, a gearing between the rotatable element and the first-mentioned rotatable member for turning the latter in a direction to wind the spring, a pivoted member having a projecting arm and a connection with the clutch member, a rock-shaft, a finger on the rock-shaft adapted to intercept the pivoted member to swing the same to trip the clutch member, an arm extending from the rock-shaft, and means actuated by the first-mentioned rotatable member for rocking the arm to actuate the rock-shaft.

3. In a starting device for internal-combustion engines, a starting shaft, a sleeve loosely mounted on said shaft, a rotatable member loosely mounted on the sleeve, a spring connected at one end to said member and at the other end to the sleeve, a rotatable element loose on the shaft, a pivoted clutch member carried by said element, a rotatable member fast on the starting shaft and having an abutment engageable by the clutch member, a gearing between the rotatable element and the first-mentioned rotatable

- member for turning the latter in a direction to wind the spring, a pivoted member having a projecting arm and a connection with the clutch member, a rock-shaft, a finger 5 on the rock-shaft adapted to intercept the arm of the pivoted member to swing said member to trip the clutch member, an arm extending from the rock-shaft, a cam engageable by the arm of the rock-shaft, a 10 pawl-and-ratchet mechanism for actuating the cam, and an eccentric driven by the first-mentioned rotatable member and operatively connected to the pawl-and-ratchet mechanism to actuate the same.
15. 4. In a starting device for internal-combustion engines, a starting shaft, a sleeve loosely mounted on said shaft, a rotatable member loosely mounted on the sleeve, a spring connected at one end to said member 20 and at the other end to the sleeve, a rotatable element loose on the shaft, a pivoted clutch member carried by said element, a rotatable member fast on the starting shaft and having an abutment engageable by the clutch 25 member, a gearing between the rotatable element and the first-mentioned rotatable member for turning the latter in a direction to wind the spring, a pivoted member having a projecting arm and a connection with the 30 clutch member, a rock-shaft, a finger on the rock-shaft adapted to intercept the arm of the pivoted member to swing said member to trip the clutch member, an arm extending from the rock-shaft, a cam engageable by 35 the arm of the rock-shaft, a pawl-and-ratchet mechanism for actuating the cam, and means actuated by the first-mentioned rotatable member for operating the pawl-and-ratchet mechanism.
40. 5. In a starting device for internal-combustion engines, a starting shaft, a sleeve loosely mounted on said shaft, a rotatable member loosely mounted on the sleeve, a spring connected at one end to said member 45 and at the other end to the sleeve, a rotatable element loose on the shaft, a pivoted clutch member carried by said element, a rotatable member fast on the starting shaft and having an abutment engageable by the clutch 50 member, a gearing between the rotatable element and the first-mentioned rotatable member for turning the latter in a direction to wind the spring, a pivoted member having a projecting arm and a connection with the 55 clutch member, a rock-shaft, a finger on the rock-shaft adapted to intercept the arm of the pivoted member to swing said member to trip the clutch member, an arm extending from the rock-shaft, a rotatable member for 60 swinging the arm to actuate the rock-shaft, and means actuated by the first-mentioned rotatable member for actuating the last-mentioned rotatable member.
65. 6. In a starting device for internal-combustion engines, a starting shaft, a sleeve

loosely mounted on said shaft, a rotatable member loosely mounted on the sleeve, a spring connected at one end to said member, and at the other end to the sleeve, a worm gear on the rotatable member, a worm 70 in mesh with said gear, a rotatable element loose on the starting shaft, a gearing between said element and the worm, a rotatable member fast on the starting shaft, a driving connection between said member 75 and the rotatable element, and means controlled by the first-mentioned rotatable member for breaking the driving connection.

7. In a starting device for internal-combustion engines, a starting shaft, a sleeve loosely mounted on said shaft, a rotatable member loosely mounted on the sleeve, a spring connected at one end to said member and at the other end to the sleeve, a rotatable element loose on the starting shaft, a rotatable member fast on the starting shaft, a driving connection between the rotatable element and the first-mentioned rotatable member for turning the latter in a 90 direction to wind the spring, a driving connection between the second-mentioned rotatable member and the rotatable element, and means controlled by the first-mentioned rotatable member for breaking the last mentioned driving connection.

8. In a starting device for internal-combustion engines, a starting shaft, a sleeve loosely mounted on said shaft, a rotatable member loosely mounted on the sleeve, a 100 spring connected at one end to said member and at the other end to the sleeve, a rotatable element loose on the shaft, a pivoted clutch member carried by said element, a rotatable member fast on the starting shaft 105 and having an abutment engageable by the clutch member, a gearing between the rotatable element and the first-mentioned rotatable member for turning the latter in a direction to wind the spring, means controlled by the first-mentioned rotatable member for tripping the clutch member, and means for locking the rotatable element when the clutch member is tripped.

9. In a starting device for internal-combustion engines, a starting shaft, a sleeve loosely mounted on said shaft, a rotatable member loosely mounted on the sleeve, a spring connected at one end to said member and at the other end to the sleeve, a rotatable element loose on the starting shaft, a rotatable member fast on the starting shaft, a driving connection between the rotatable element and the first-mentioned rotatable member for turning the latter in a direction to wind the spring, a driving connection between the second-mentioned rotatable member and the rotatable element, means controlled by the first-mentioned rotatable member for breaking the last-mentioned 115 120 125 130

driving connection, and means for locking the rotatable element when the aforesaid driving connection is broken.

10. In a starting device for internal-combustion engines, a starting shaft, a sleeve loosely mounted on said shaft, a rotatable member loosely mounted on the sleeve, a spring connected at one end to said member and at the other end to the sleeve, a rotatable element loose on the shaft and operatively connected to the rotatable member to turn the same in a direction to wind the spring, a pivoted clutch member carried by said element, a rotatable member fast on the starting shaft and having an abutment engageable by the clutch member, a clutch releasing device, a swinging finger adapted to intercept the clutch releasing device to actuate the same, a detent for locking the rotatable element when the clutch member is released, and means controlled by the first-mentioned rotatable member for actuating the finger and the detent.

11. In a starting device for internal-combustion engines, a starting shaft, a sleeve loosely mounted on said shaft, a rotatable member loosely mounted on the sleeve, a spring connected at one end to said member and at the other end to the sleeve, a rotatable element loose on the shaft and operatively connected to the rotatable member to turn the same in a direction to wind the spring, a pivoted clutch member carried by said element, a rotatable member fast on the starting shaft and having an abutment engageable by the clutch member, a clutch releasing device, a swinging finger adapted to intercept the clutch releasing device to actuate the same, a detent for locking the rotatable element when the clutch member is released, means controlled by the first-mentioned rotatable member for actuating the finger, and a connection between said finger and the detent for actuating the latter when the finger is actuated.

12. In a starting device for internal-combustion engines, a starting shaft, a sleeve loosely mounted on the shaft, a rotatable member loosely mounted on the sleeve, a spring connected at one end to said member, and at the other end to the sleeve, means for winding the spring from the starting shaft, coöperating clutch members on the starting shaft and the sleeve, respectively, a lever having means for locking the clutch member of the sleeve, an arm extending from the lever, a cam engageable by the arm for holding the lever in releasing position, and means actuated by the sleeve for operating the cam to release the arm and allow the lever to assume its locking position.

13. In a starting device for internal-combustion engines, a starting shaft, a sleeve loosely mounted on the shaft, a rotatable

member loosely mounted on the sleeve, a spring connected at one end to said member, and at the other end to the sleeve, means for winding the spring from the starting shaft, coöperating clutch members on the starting shaft and the sleeve, respectively, a lever having means for locking the clutch member of the sleeve, an arm extending from the lever, a cam engageable by the arm for holding the lever in releasing position, and means actuated by the sleeve for operating the cam to release the arm and allow the lever to assume its locking position, said means comprising a pawl-and-ratchet mechanism connected to the cam, and an eccentric on the sleeve and operatively connected to the pawl-and-ratchet mechanism.

14. In a starting device for internal-combustion engines, a starting shaft, a sleeve loosely mounted on the shaft, a rotatable member loosely mounted on the sleeve, a spring connected at one end to said member, and at the other end to the sleeve, means for winding the spring from the starting shaft, coöperating clutch members on the starting shaft and the sleeve, respectively, a lever having means for locking the clutch member of the sleeve, a cam on the clutch member of the sleeve for forcing the lever to release position, an arm extending from the lever, a cam engageable by the arm for holding the lever in releasing position, and means actuated by the sleeve for operating the cam to release the arm and allow the lever to assume its locking position.

15. In a starting device for internal combustion engines, a starting shaft, a member rotatable independently of the shaft, a second rotatable member, a spring connected at its respective ends to said members, a rotatable element loose on the shaft, a pivoted clutch member carried by said element, a rotatable member fast on the starting shaft and having an abutment engageable by the clutch member, a gearing between the rotatable element and the second-mentioned rotatable member for turning the latter in a direction to wind the spring, and means controlled by said second-mentioned rotatable member for tripping the clutch member.

16. In a starting device for internal combustion engines, a starting shaft, a member rotatable independently of the shaft, a second rotatable member, a spring connected at its respective ends to said members, a rotatable element loose on the shaft, a pivoted clutch member carried by said element, a rotatable member fast on the starting shaft and having an abutment engageable by the clutch member, a gearing between the rotatable element and the second-mentioned rotatable member for turning the latter in a direction to wind the spring, a pivoted member having a projecting arm and a connection with the clutch member, a rock-

shaft, a finger on the rock-shaft adapted to intercept the pivoted member to swing the same to trip the clutch member, an arm extending from the rock-shaft, and means actuated by the second-mentioned rotatable member for rocking the arm to actuate the rock-shaft.

17. In a starting device for internal combustion engines, a starting shaft, a member rotatable independently of the shaft, a second rotatable member, a spring connected at its respective ends to said members, a rotatable element loose on the shaft, a pivoted clutch member carried by said element, a rotatable member fast on the starting shaft and having an abutment engageable by the clutch member, a gearing between the rotatable element and the second-mentioned rotatable member for turning the latter in a direction to wind the spring, a pivoted member having a projecting arm and a connection with the clutch member, a rock-shaft, a finger on the rock-shaft adapted to intercept the arm of the pivoted member to swing said member to trip the clutch member, an arm extending from the rock-shaft, a cam engageable by the arm of the rock-shaft, a pawl-and-ratchet mechanism for actuating the cam, and an eccentric driven by the second-mentioned rotatable member and operatively connected to the pawl-and-ratchet mechanism to actuate the same.

18. In a starting device for internal combustion engines, a starting shaft, a member rotatable independently of the shaft, a second rotatable member, a spring connected at its respective ends to said members, a rotatable element loose on the shaft, a pivoted clutch member carried by said element, a rotatable member fast on the starting shaft and having an abutment engageable by the clutch member, a gearing between the rotatable element and the second-mentioned rotatable member for turning the latter in a direction to wind the spring, a pivoted member having a projecting arm and a connection with the clutch member, a rock-shaft, a finger on the rock-shaft adapted to intercept the arm of the pivoted member to swing said member to trip the clutch member, an arm extending from the rock-shaft, a cam engageable by the arm of the rock-shaft, a pawl-and-ratchet mechanism for actuating the cam, and means actuated by the second-mentioned rotatable member for operating the pawl-and-ratchet mechanism.

19. In a starting device for internal combustion engines, a starting shaft, a member rotatable independently of the shaft, a second rotatable member, a spring connected at its respective ends to said members, a rotatable element loose on the shaft, a pivoted clutch member carried by said element, a rotatable member fast on the starting shaft and having an abutment engageable by the

clutch member, a gearing between the rotatable element and the second-mentioned rotatable member for turning the latter in a direction to wind the spring, a pivoted member having a projecting arm and a connection with the clutch member, a rock-shaft, a finger on the rock-shaft adapted to intercept the arm of the pivoted member to swing said member to trip the clutch member, an arm extending from the rock-shaft, a rotatable member for swinging the arm to actuate the rock-shaft, and means actuated by the second-mentioned rotatable member for actuating the last-mentioned rotatable member.

20. In a starting device for internal combustion engines, a starting shaft, a member rotatable independently of the shaft, a second rotatable member, a spring connected at its respective ends to said members, a worm gear on the second-mentioned rotatable member, a worm in mesh with said gear, a rotatable element loose on the starting shaft, a gearing between said rotatable element and the worm, a rotatable member fast on the starting shaft, a driving connection between the last-mentioned rotatable member and the rotatable element, and means controlled by the second-mentioned rotatable member for breaking the driving connection.

21. In a starting device for internal combustion engines, a starting shaft, a member rotatable independently of the shaft, a second rotatable member, a spring connected at its respective ends to said members, a rotatable element loose on the starting shaft, a rotatable member fast on the starting shaft, a driving connection between the rotatable element and the second-mentioned rotatable member for turning the latter in a direction to wind the spring, a driving connection between the last-mentioned rotatable member and the rotatable element, and means controlled by the second-mentioned rotatable member for breaking the last-mentioned driving connection.

22. In a starting device for internal combustion engines, a starting shaft, a member rotatable independently of the shaft, a second rotatable member, a spring connected at its respective ends to said members, a rotatable element loose on the shaft, a pivoted clutch member carried by said element, a rotatable member fast on the starting shaft and having an abutment engageable by the clutch member, a gearing between the rotatable element and the second-mentioned rotatable member for turning the latter in a direction to wind the spring, means controlled by the second-mentioned rotatable member for tripping the clutch member, and means for locking the rotatable element when the clutch member is tripped.

23. In a starting device for internal com-

bustion engines, a starting shaft, a member rotatable independently of the shaft, a second rotatable member, a spring connected at its respective ends to said members, a rotatable element loose on the starting shaft, a rotatable member fast on the starting shaft, a driving connection between the rotatable element and the second-mentioned rotatable member for turning the latter in a direction to wind the spring, a driving connection between the last-mentioned rotatable member and the rotatable element, means controlled by the second-mentioned rotatable member for breaking the last-mentioned driving connection, and means for locking the rotatable element when the aforesaid driving connection is broken.

24. In a starting device for internal combustion engines, a starting shaft, a member rotatable independently of the shaft, a second rotatable member, a spring connected at its respective ends to said members, a rotatable element loose on the starting shaft and operatively connected to the second-mentioned rotatable member to turn the same in a direction to wind the spring, a pivoted clutch member carried by said element, a rotatable member fast on the starting shaft and having an abutment engageable by the clutch member, a clutch-releasing device, a swinging finger adapted to intercept the clutch releasing device to actuate the same, a detent for locking the rotatable element when the clutch member is released, and means controlled by the second-mentioned rotatable member for actuating the finger and the detent.

25. In a starting device for internal combustion engines, a starting shaft, a member rotatable independently of the shaft, a second rotatable member, a spring connected at its respective ends to said members, a rotatable element loose on the shaft and operatively connected to the second-mentioned rotatable member to turn the same in a direction to wind the spring, a pivoted clutch member carried by said element, a rotatable member fast on the starting shaft and having an abutment engageable by the clutch member, a clutch-releasing device, a swinging finger adapted to intercept the clutch-releasing device to actuate the same, a detent for locking the rotatable element when the clutch member is released, means controlled by the second-mentioned rotatable member for actuating the finger, and a connection between said finger and the detent for

actuating the latter when the finger is actuated.

26. In a starting device for internal combustion engines, a starting shaft, a member rotatable independently of the shaft, a spring connected to said member for turning the same, coöperating clutch members on the starting shaft and the aforesaid rotatable member, respectively, a lever having means for locking the clutch member of the rotatable member, an arm extending from the lever, a cam engageable by the arm for holding the lever in releasing position, and means actuated by the rotatable member for operating the cam to release the arm and allow the lever to assume its locking position.

27. In a starting device for internal combustion engines, a starting shaft, a member rotatable independently of the shaft, a spring connected to said member for turning the same, coöperating clutch members on the starting shaft and the aforesaid rotatable member, respectively, a lever having means for locking the clutch member of the rotatable member, an arm extending from the lever, a cam engageable by the arm for holding the lever in releasing position, and means actuated by the rotatable member for operating the cam to release the arm and allow the lever to assume its locking position, said means comprising a pawl-and-ratchet mechanism connected to the cam, and an eccentric on the rotatable member operatively connected to the pawl-and-ratchet mechanism.

28. In a starting device for internal combustion engines, a starting shaft, a member rotatable independently of the shaft, a spring connected to said member for turning the same, coöperating clutch members on the starting shaft and the aforesaid rotatable member, respectively, a lever having means for locking the clutch member of the rotatable member, a cam on the clutch member of the rotatable member for forcing the lever to release position, an arm extending from the lever, a cam engageable by the arm for holding the lever in releasing position, and means actuated by the rotatable member for operating the cam to release the arm and allow the lever to assume its locking position.

In testimony whereof I affix my signature in presence of two witnesses.

PHILIP POVLOTZKY.
